UNITED STATES PATENT OFFICE.

WILLIAM P. LAYTON, OF CHICAGO, ILLINOIS, ASSIGNOR TO GARRETT GO-CART & CARRIAGE COMPANY, OF CHICAGO, ILLINOIS, A CORPORATION OF ILLINOIS.

DESIGN FOR A BODY AND HOOD OF CHILDREN'S CARRIAGES.

46,389.

Specification for Design.

Patented Sept. 8, 1914.

Application filed May 16, 1914. Serial No. 839,182. Term of patent 14 years.

To all whom it may concern:

Be it known that I, WILLIAM P. LAYTON, a citizen of the United States, residing at Chicago, in the county of Cook and State of Illinois, have invented a new, original, and ornamental Design for the Bodies and Hoods of Children's Carriages, of which the following is a specification, reference being had to the accompanying drawing, forming a part thereof.

Figure 1 is a side elevation of the body and hood of a child's carriage showing my new design. Fig. 2 is a front elevation of

the body and hood. Fig. 3 is a transverse sectional view of the so-called roll at the front and rear edges of the hood, the object of the view being to show the exterior form of said roll.

I claim:

The ornamental design for the body and hood of children's carriages, as shown.

WILLIAM P. LAYTON.

Witnesses:

GEORGE L. CHINDAHL,
MARGARET H. MANN.
